US0D1042449S

(12) **United States Design Patent** (10) **Patent No.:** **US D1,042,449 S**
(45) **Date of Patent:** **** Sep. 17, 2024**

(54) **ELECTRONIC DEVICE**

(71) Applicant: **OPEN WORKSPACE, LLC**, Highland Park, IL (US)

(72) Inventor: **David Adler**, Highland Park, IL (US)

(73) Assignee: **Open Workspace, LLC**, Highland Park, IL (US)

(**) Term: **15 Years**

(21) Appl. No.: **29/833,836**

(22) Filed: **Apr. 7, 2022**

Related U.S. Application Data

(63) Continuation-in-part of application No. 17/548,832, filed on Dec. 13, 2021.

(51) **LOC (14) Cl.** **14-02**

(52) **U.S. Cl.**

USPC **D14/371**

(58) **Field of Classification Search**

USPC D12/192, 415; D14/305, 306, 307, 334, D14/335, 336, 337, 339, 340, 356, 371, D14/372, 374, 375, 376, 377, 378, 379, D14/380, 381, 382, 432, 439, 448, 449, D14/450, 451, 452, 125, 126, 127, 129, D14/134, 239

CPC G06F 1/1601; G06F 1/1603; G06F 1/1605; G06F 1/1607; G06F 1/1609; G06F 1/1611; G02F 1/133; G02F 1/1333; G02F 1/133308; H04N 5/64; H04N 5/645; H04N 5/655

(57) **CLAIM**

The ornamental design for an electronic device, as shown and described.

DESCRIPTION

FIG. 1 is a perspective view of an electronic device showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings depict portions of the electronic device that form no part of the claimed design.

1 Claim, 8 Drawing Sheets
